CHARLES J. COOPER, OF MOLINE, ILLINOIS, ASSIGNOR OF ONE-HALF TO H. W. COOPER
SADDLERY HARDWARE MFG. COMPANY, OF MOLINE, ILLINOIS, A CORPORATION OF
ILLINOIS.

HARNESS LOOP OR BILLET.

1,111,880.

Specification of Letters Patent. Patented Sept. 29, 1914.

Application filed January 19, 1911. Serial No. 603,438.

To all whom it may concern:

Be it known that I, CHARLES J. COOPER, a citizen of the United States, residing in Moline, in the county of Rock Island, in the 5 State of Illinois, have invented certain new and useful Improvements in Harness Loops or Billets, of which the following is a specification.

This invention relates to the general art 10 of harness, and has reference more particularly to a new and improved harness loop or billet which may be used at various places in a complete harness where a leather loop is required.

15 Among the salient objects of the invention are, to provide a device which will obviate separating strains on the stitching; to provide a device wherein the pull on the line will be straight and substantially in the 20 direction of the line itself; to provide a device in which the coöperating strap and buckle may be readily and easily assembled and disassembled; to provide a device which will possess a low substantially flat effect at 25 the buckle and without the usual bow or hump effect generally characteristic of these devices; and, in general, to provide a neat, attractive and highly serviceable harness accessory of the character specified.

30 With these objects in view, the invention consists in the novel device hereinafter described and definitely pointed out in the claims.

In the accompanying drawing I have 35 shown one practical form in which the invention may be embodied, and in which—

Figure 1 is a top plan view of my improved harness loop. Fig. 2 is a perspective elevation of the same. Fig. 3 is a side elevation, in central longitudinal section through the buckle; and Fig. 4 is an edge elevation of the billet-strap detached from the buckle.

Referring to the drawing, and first describing the buckle-member, this latter comprises a substantially rectangular frame made up of the parallel sides 5, rear cross-bar 6, and front cross-bar 7. Where the side bars 5 merge into the front cross-bars 7, the outer edges of said side bars are outwardly inclined as shown at 8 in Fig. 1, thereby producing a buckle-frame having an outwardly flared or widened front portion which enables the front cross-bar 7 to be made flatter and thinner than would otherwise be 55 possible, and which is also sometimes of ad-

vantage in preventing the drawing of the buckle through another part of the harness, such as a terret ring.

Between the sides 5 of the buckle-frame are two rigid cross-bars 9 and 10. The lower side of the rear cross-bar 9 is substantially flush with the lower edges of the side bars 5, while its upper side lies slightly below the plane of the upper edges of the side bars 5, as clearly shown in Fig. 3. The cross-bar 9 has formed thereon and centrally thereof a rigid upstanding stud 11 of sufficient height to engage and pass through registering holes in at least two thicknesses of the leather strap; said stud serving the function of the usual pivoted buckle-tongue to anchor the buckle frame on the line. The forward cross-bar 10 is downwardly off-set somewhat in excess of the thickness of the strap or line relatively to the rear cross-bar 9, as clearly shown in Fig. 3, and constitutes, in connection with the front cross-bar 7, a guide or keeper for the inner end of the loop.

Referring to the billet strap, 12 designates the main line or strap, to the lower or under surface of which is secured, as by stitching indicated at 13, or otherwise, one end of the lower limb 14^a of the loop member 14; the limb 14^a of the loop member being attached to the main line 12 somewhat in rear of the end of the latter, thereby gives to the end portion of the main line 12 the character of a short free tongue 15 lying between the lower and upper limbs 14^a and 14^b of the loop. The tongue 15 and upper loop member 14^b are provided with apertures 16 and 17, respectively, adapted to engage the stud 11 in the manner clearly shown in Fig. 3.

In assembling the strap and buckle, the buckle is slid rear end foremost over the free end of the loop, the latter passing between the lower cross-bar 10 and the upper cross-bars 7 and 9. The buckle is slid back on the loop until the tongue 15 is entered between the cross-bars 6 and 9, its aperture 16 being engaged with the stud 11, and its free end being bent down beneath the front cross-bar 7. The free end portion of the loop 14 represented by the upper limb 14^b is then entered beneath the front cross-bar 7 and above the free end of the tongue 15, and by bending the same upwardly its free end is passed beneath the rear cross-bar 6, whereupon by flattening the bowed portion the aperture 17 is engaged with the stud 11. This manner

of assembling the buckle and strap is the simplest and easiest method, but, of course, the parts may be otherwise assembled, and the particular mode of assembling is wholly immaterial to the invention. The described device forms a loop or billet of great strength, very compact, and of neat appearance.

By passing both the upper and lower members of the loop between the upper and lower cross-bars of the buckle in advance of the point of attachment of the loop member to the main line member, all transverse separating or breaking strains upon the stitching or other attaching means are avoided; and, further, by providing the tongue 15 and engaging it with the stud 11, the strain on the stitching 13 or other attaching means is reduced to one-half the entire pull or strain on the line 12. One of the greatest advantages of this billet is that the buckle can be detached or applied at will to the straps without ripping out stitches, removing rivets, punching additional holes, or additional stitching, and still have all of the desirable qualities of the stitched or riveted billet.

I claim—

1. A harness loop, comprising, in combination, a buckle having a rigid tongue, a line-strap having an integral free end portion passed through said buckle and engaged with the tongue thereof, and a loop-strap having one longitudinal limb thereof at-

tached at its inner end to the underside of said line-strap in rear of said buckle and its other longitudinal limb passed through said buckle and above the free end portion of said line-strap and also engaged with the tongue of said buckle, substantially as described. 35

2. A harness loop, comprising, in combination, a buckle consisting of a rectangular frame having front and rear end cross-bars and two intermediate cross-bars, the rear-most of said intermediate cross-bars having a rigid upstanding stud and the foremost of 40 said intermediate cross-bars being downwardly off-set relative to said rear-most intermediate cross-bar, a line-strap having an integral free end portion passed through said buckle above both of said intermediate cross-bars and apertured to engage said stud, and a loop-strap having one longitudinal limb 45 thereof attached at its inner end to the underside of said line-strap in rear of said buckle and passed between said intermediate cross-bars, and its other limb passed through said buckle beneath said end cross-bars and above both said intermediate cross-bars and the free end portion of said line-strap and apertured to engage said stud, substantially 50 55 as described. 60

CHARLES J. COOPER.
